UNITED STATES PATENT OFFICE.

BERTHIL M. LINDHE, OF MADISON, WISCONSIN.

RACK.

1,404,778.

Specification of Letters Patent. Patented Jan. 31, 1922.

Application filed June 9, 1921. Serial No. 476,314.

To all whom it may concern:

Be it known that I, BERTHIL M. LINDHE, a citizen of the United States, residing at Madison, in the county of Dane and State 5 of Wisconsin, have invented a new and useful Rack, of which the following is a specification.

This invention relates to racks and more particularly to racks for supporting pamphlets, sheets or the like to permit persons to readily and easily remove one or more of 10 said pamphlets.

The primary object of the invention is to provide adjustable arms forming a part of 15 the rack, thereby adapting the device for use in supporting pamphlets or sheets of various sizes.

A further object of the invention is to provide a support for the arm, the support having guideways formed by turning the side edges thereof inwardly.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:

Figure 1 is a plan view of a rack constructed in accordance with the present invention.

Figure 2 is a side elevational view of the same.

Figure 3 is a plan view of the rack.

Figure 4 is a sectional view taken on line 40 4-4 of Figure 1.

Referring to the drawing in detail, the device includes a base plate 5 which has inwardly extending end portions 6 which lie in spaced relation with the base plate proper 45 to provide guideways for the spaced leg members 7.

These leg members 7 are connected at one of their respective ends, as by means of the outwardly extending flange 8, which has an 50 upwardly extending flange 9 formed integral therewith, the flange 9 lying in spaced relation with the legs 7 to accommodate the article supported by the rack.

Supported over the plate 5 is a plate 9', 55 which plate is provided with outwardly and inwardly extending flanges 10, and inwardly

extending flanges 11, the flanges 10 and 11 being disposed on opposite sides of the plate 9' to accommodate laterally movable arms 12 and 13, each arm being provided with a right angled portion 14 which terminates in an inwardly extending portion 15 adapted to lie in spaced relation with the arm forming a part thereof, so that the booklet may be supported therebetween.

The plate 9' is provided with extensions 16 formed intermediate the upper and lower edges thereof, which extensions are apertured to accommodate suitable securing nails by means of which the device may be secured to a wall or other suitable supporting means.

From the foregoing it will be seen that the booklets or pamphlets to be supported by the rack are first centered on the rack, whereupon the adjustable arms are moved inwardly to grasp the booklets or pamphlets.

It is therefore obvious that due to the construction of the rack as disclosed, the pamphlets or booklets supported thereby, may be grasped at one side of the rack, and easily removed.

Having thus described the invention, what is claimed as new is:

1. A rack including a base plate having downwardly and inwardly extending portions providing guideways, a vertically movable arm having a pair of legs positioned within the guideways, said arm including an upwardly and inwardly extending portion to provide a support, and laterally movable arms operating above the first mentioned arm.

2. A rack including a base plate having downwardly and inwardly extending portions providing guideways, an arm movable within the guideway, laterally extending arms operating above the first mentioned arm, means for supporting the laterally movable arms, and said laterally movable arms having right angled ends providing supports.

3. A rack including a base plate having downwardly and inwardly extending portions providing guideways, an arm movable in the guideways, opposed arms mounted above the first mentioned arm, and adapted to move in opposite directions, and said arms having supporting members forming a part thereof.

4. A rack including a base plate having guideways, an arm movable within the guideways, a plate mounted above the arm

and having downwardly and inwardly extending portions, said plate having upwardly and inwardly extending portions, arms supported on the last mentioned plate,
5 and said arms having supporting members forming a part thereof.

In testimony that I claim the foregoing as

my own, I have hereto affixed my signature in the presence of two witnesses.

BERTHIL M. LINDHE.
